[57] CLAIM

The ornamental design for portable collapsible laptop computer table, as shown and described.

DESCRIPTION

FIG. 1 is a front perspective view of the portable collapsible laptop computer table in an opened configuration, as it would normally be used, showing my new design;

FIG. 2 is a front elevational view thereof;

FIG. 3 is a right side elevational view thereof with the left side view being identical;

FIG. 4 is a rear elevational view thereof;

FIG. 5 is a top plan view thereof;

FIG. 6 is a bottom plan view thereof; and,

FIG. 7 is a front perspective view thereof in a collapsed alternate position.
